[57] CLAIM

The ornamental design for a license plate frame, as shown and described.

DESCRIPTION

FIG. 1 is a top plan view of a license plate frame showing my new design;

FIG. 2 is a left side elevational view, the right side elevational view being the mirror image thereof;

FIG. 3 is a front elevational view thereof;

FIG. 4 is a bottom plan view thereof;

FIG. 5 is a rear elevational view thereof;

FIG. 6 is a top plan view of a second embodiment thereof;

FIG. 7 is a left side elevational view of the second embodiment, the right side elevational view being the mirror image thereof;

FIG. 8 is a front elevational view of the second embodiment thereof;

FIG. 9 is a bottom plan view of the second embodiment thereof;

FIG. 10 is a rear elevational view of the second embodiment thereof;

FIG. 11 is a top plan view of a third embodiment thereof;

FIG. 12 is a right side elevational view of the third embodiment, the left side elevational view being the mirror image thereof;

FIG. 13 is a front elevational view of the third embodiment thereof;

FIG. 14 is a bottom plan view of the third embodiment thereof; and,

FIG. 15 is a rear elevational view of the third embodiment thereof.
